FIG. 4

FIG. 5

FIG. 6

FIGURE 1 is a front elevational view of a jug showing my new design;

FIGURE 2 is a side elevational view thereof;

FIGURE 3 is a rear elevational view thereof;

FIGURE 4 is a top plan view thereof;

FIGURE 5 is a bottom plan view thereof.

FIGURE 6 is a sectional view taken along line 6—6 of FIGURE 2.

The dominant features of my invention reside in the top portion which includes the handle integrally formed with the collar about the neck portion in combination with

the grooves of the upper inclined portion of the jug as shown.

I claim:

The ornamental design for a jug, substantially as shown and described.
